COMBINATION STORAGE CABINET AND SINK
FOR LAUNDRY OR THE LIKE

Aman U. Khan, St. Joseph, Mich., assignor to Whirlpool
Corporation, a corporation of Delaware

Filed June 16, 1966, Ser. No. 2,702

Term of patent 14 years

(Cl. D23—59)

Fig. 1.

Fig. 2.

Fig. 1.

Fig. 2.

Fig. 3.

The dominant features of my design reside in the portions shown in full lines.

I claim:

The ornamental design for a combination storage cabinet and sink for laundry or the like, as shown and described.
